COMBINATION FUEL DISTRIBUTING, SPEED
GOVERNING, AND STARTING DEVICE FOR
DIESEL ENGINES

Peter Das, Peekskill, N. Y.

Application December 5, 1940, Serial No. 368,648

3 Claims. (Cl. 192—20)

This invention relates to new and useful improvements in Diesel engines and has more particular references to a combination fuel distributing, speed governing and starting device for Diesel engines.

More particularly, the invention proposes the construction of a device as mentioned adapted to distribute fuel oil to the cylinders of the Diesel engine, and to regulate its speed, and to start the engine. It is proposed to so construct the device that it may perform these functions individually, or may combine two or more, as desired. With the elimination of certain of these functions it is possible to eliminate certain of the parts of the device used to perform these functions. An important feature of the invention resides in the simplicity and accuracy of the device with which these three duties may be performed, combined or used separately.

More specifically, the invention proposes to characterize the device by a fuel oil inlet valve control cam slidably and non-rotatively mounted on the drive shaft for the cam or cams actuating the fuel inlet valve or valves, and driven from the Diesel engine shaft, and a novel arrangement for operating said cam. In one form of the invention an automatic system is provided for the control of this cam. In another embodiment of the invention this cam may be controlled manually, in which case the device merely functions as a fuel distributing device.

It is proposed to automatically work the cam for speed control of the Diesel engine. With this purpose in mind, a screw is coaxially mounted on the drive shaft and connected with one end of the cam and threadedly engages an internally threaded wheel rotatively stationarily held and connected with a lead motor. It is proposed to so arrange the parts that should the wheel rotate faster than the drive shaft, said screw will move in one direction for moving said cam to increase said fuel supply to the Diesel engine, and should said wheel rotate slower than the drive shaft, said screw will move in the other direction for moving the cam to decrease said fuel supply and thus regulate the speed of the Diesel engine.

Still further the invention contemplates controlling the speed of the lead motor for controlling the speed of the Diesel engine.

It is another object of this invention to provide catch elements on the screw on opposite sides of said wheel cooperative with complementary catches on the sides of the wheel, by which the lead motor may drive the Diesel engine for

starting the same, or the Diesel engine may drive the lead motor until the speed of the Diesel engine recedes to normal.

In another form of the invention, it is proposed that the lead motor be of sufficient capacity to drive the Diesel engine and then the device may be used as a starting device for the Diesel engine. In another form of the invention, it is proposed that a separate starter be used for the Diesel engine, and that the lead motor be used merely for regulating the speed of the Diesel engine. In this latter arrangement the lead motor may be quite small as it merely must overcome frictional resistance. With this arrangement the motor has no other load. However, it should be borne in mind that the Diesel engine will follow the lead motor and consequently as loads are thrown "on" and "off" of the Diesel engine, it will speed up or slow down and then adjust itself until it again reaches the speed of the lead motor. Since it is a simple matter to control the speed of the lead motor, it is a simple matter to control the speed of the Diesel engine. With this arrangement the Diesel engine may be stopped by stopping the lead motor.

Still further the invention proposes a certain construction of the fuel oil inlet valve control cam, which construction will control the fuel oil valve at correctly timed intervals, in connection with the speed of the Diesel engine, by starting the valve "lift" at the right instant corresponding with the maximum compression in the cylinder of the Diesel engine, to always correspond with the same angular position of the drive shaft thereof. It is proposed to so construct this cam that it merely controls the period of the valve lift. When it is desired that more fuel be supplied the cam will keep the valve lifted for a longer period, and when less fuel is required the period will be shorter.

Still further it is proposed to characterize the control valve cam by the fact that it has a cylindrical portion concentric with its drive shaft and an operator portion consisting of a cylindrical portion eccentric with the drive shaft with its axis parallel to said concentric portion and its surface penetrating the surface of said concentric portion. It is proposed that the operator portion of the cam have a longitudinally extending lead edge for controlling the beginning of the opening of the inlet valve. It is proposed that the operator portion have an opposed inclined edge, so that the width across these edges

determines the duration of the valve lift at any particular section of the cam.

In that form of the invention in which the fuel inlet valve control cam is automatically moved by the screw and lead motor previously mentioned, the closing of the fuel inlet valve will be determined by the angle at which the lead motor is ahead of the Diesel engine.

Still further it is proposed that the fuel oil inlet valve be changed, or its seat be changed, for either a smaller or a larger fuel oil supply for changes in the size and speed of Diesel engines.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a fragmentary plan view disclosing a combination fuel oil distributing, speed governing and starting device for Diesel engines constructed in accordance with this invention, certain parts being broken to disclose the interior construction.

Fig. 2 is a fragmentary reduced view of a portion of Fig. 1 showing the parts in a different position.

Fig. 3 is another fragmentary reduced view of a portion of Fig. 1 showing the parts in still another position.

Fig. 4 is a fragmentary sectional view taken on the line 4—4 of Fig. 1, to which a sectional view of a fuel oil inlet valve, and associated control valves, have been added.

Fig. 5 is a vertical sectional view taken on the line 5—5 of Fig. 1.

Fig. 6 is a vertical sectional view taken on the line 6—6 of Fig. 1.

Fig. 7 is a vertical sectional view taken on the line 7—7 of Fig. 1.

Fig. 8 is a vertical sectional view taken on the line 8—8 of Fig. 1.

Fig. 9 is a vertical sectional view taken on the line 9—9 of Fig. 1.

Fig. 10 is a plan view of a combination fuel oil distributing, speed governing and starting device for Diesel engines constructed in accordance with a modified form of this invention.

Fig. 11 is a fragmentary plan view of a combination fuel oil distributing, speed governing and starting device for Diesel engines constructed in accordance with still another form of this invention.

In the form of the invention illustrated in Figs. 1—9 inclusive, the combination fuel oil distributing, speed governing and starting device for Diesel engines includes a drive shaft 12 for the cam or cams actuating the fuel inlet valve or valves for controlling the fuel supply to the Diesel engine, and adapted to be driven from the Diesel engine shaft by the usual sprocket wheel and chain, or by a set of gears, so that the shaft 12 makes one revolution for each two revolutions of the Diesel engine in the case of a four-cycle engine, and equal revolutions in the case of a two-cycle engine.

A fuel oil inlet valve control cam 14 is slidably and non-rotatively mounted on the drive shaft 12 and has an inclined longitudinally extending operator portion 15 for controlling the fuel oil inlet valve. The slidable and non-rotative mounting of this cam is accomplished with keys 16 mounted on the shaft 12 and cooperative with

the internal bore of the cam 14. The operator portion 15 has its lead side 15a extending longitudinally of the cam 14, and the side 15b to the rear of the lead side 15a, inclined for the purpose as hereinafter more fully explained.

A screw 17 is coaxially mounted on the drive shaft 12 and is connected with one end of the cam 14. The screw and cam may be integral, or connected together, as desired. The screw 17 may also slidably engage the keys 16, though this is not necessary since it is connected with the cam 14 which is slidably and non-rotatively mounted on the drive shaft 12. An internally threaded wheel 18 threadedly engages the screw 17. This wheel 18 is rotatively, non-shiftably held by a thrust bearing. More specifically, the wheel 18 has an integral, or connected hollow hub 19, which extends into a casing 20. A flange 21 is mounted on a reduced outer end portion of the hub 19. The flange 21 is fixedly held in position by several lock nuts 22. Thrust bearings 23 are mounted in the casing 20, and engage the opposite sides of the flange 21 for non-shiftably holding the wheel 18. The arrangement is such that the wheel 18 may rotate but cannot shift along the length of the drive shaft 12.

A variable speed lead motor 24 is provided for driving the wheel 18, whereby should the wheel 18 rotate faster than the drive shaft 12, said screw 17 will move in one direction, and should the wheel 18 rotate slower than the drive shaft 12, said screw 17 will move in the other direction. The lead motor 24 is connected with the wheel 18 by a gear 25 mounted on the shaft of the motor 24 and meshing with gear teeth formed on the wheel 18. It is proposed that the lead motor 24 be driven from an electric storage battery, or from any other source of electricity. The speed of this motor may be regulated by means of regulating the strength of the field, or by regulating the armature voltage, or in the case of an A. C. motor by changing the number of cycles, or by changing the number of poles of the motor. Further details of varying the speed of this motor will not be given in this specification as it forms no part of the invention and such constructions are generally known in the art.

Catch elements 26 and 27 are mounted upon the ends of the screw 17, and are cooperative with complementary catch elements 28 and 29 mounted on the sides of the wheel 18 by which the lead motor may drive the Diesel engine for starting the Diesel engine, or the Diesel engine may drive the lead motor until the speed of the Diesel engine reaches normal. During the normal operation of the Diesel engine the screw 17 will be in a midway position through the wheel 18. If the drive shaft 12 rotates at the same speed as the lead motor 24, the screw 17 will maintain this position. However, if there is a difference of speed, the screw 17 will move in one direction or the other, depending whether the lead motor 24 is faster, or slower than the shaft 12. If the screw 17 moves to its extreme positions, in one direction or the other, the catches on one side, or the other side of the wheel 18, will engage each other, and then the wheel 18 will be coupled with the screw 17 as a unit. It is at this point that the lead motor 24 may drive the shaft 12, or the shaft 12 may drive the lead motor. When a "balance" is again reached, and the Diesel engine is running at the same speed as the lead motor, the screw 17 will be in an intermediate position with respect to

the wheel 18. This will be better understood as this specification proceeds.

The cam 14 controls the fuel oil valve 30 of the Diesel engine. This valve 30 has a control stem 31 which normally is urged outwards by an expansion spring 32 to close the valve. The stem 31 may be lifted for opening the valve. The valve 30 is in the fuel supply pipe 33 leading from a pressure tank in which the fuel oil is pumped by a separate pump and kept under pressure sufficiently high to overcome the compression in the cylinders, and resistance in the fuel lines and valve and spray nozzles, as is customary in a Diesel engine. A throttle valve 34 is conveniently placed after the inlet valve 30, and a shut off valve 35 is installed before the inlet valve 30.

The cam 14 has its operator portion 15 formed by a portion of a cylinder having its center at the point 36 (see Fig. 4). The lead edge of the operator portion 15 joins the surface of the cam 14 which is substantially of cylindrical shape at the point 37. The inclined edge 15b of the operator portion 15 continues into a portion 38 which is a part of a cylinder having its axis concentric with the shaft 12, that is, the center point 39. It will thus be noted that the active part of the cam 14 is formed from two portions of two cylinders, one of which is concentric with the drive shaft 12 and the other is eccentric.

The eccentric portion 15 functions in lifting the stem 31 for opening the valve 30. The concentric portion 38 does not support the stem 31 so that the valve is closed during the period that this portion is engaging the bottom of the stem. Figs. 5-9 inclusive represent various sections through the cam 14, these sections being taken on the lines shown in Fig. 1. From these sections it will be readily seen that the operator portion 15 is of different widths along the length of the cam, and that for each of these sections, the lead edge 15a is at the identical point on the circumference of the cam. The operator portion 15 is of different angular sizes as may be noted from the difference in the angles between the line AB and the line CD inscribed on Figs. 5-9 inclusive, and Fig. 4.

The operation of the device is as follows:

Assume that it is desired to start the Diesel engine. The shut off valve 35 is fully opened and the throttle valve 34 is partially opened. Then the lead motor 24 is started. The lead motor will drive the screw 17 until the catches 26 and 28 engage each other, and then the lead motor will drive the shaft 12 and thus the Diesel engine. When the catches 26 and 28 engage each other, the cam 14 will be in a position in which the wide portion of the operator portion 15 engages the stem 31 of the fuel supply inlet valve 30 supplying maximum fuel to the Diesel engine. During the starting period the device acts as a starter. As soon as a few explosions occur and the Diesel engine is running, the throttle valve 34 may be completely opened and the engine is in normal operation. When this occurs, the screw 17 will assume an intermediate position through the wheel 18. Thus the cam 14 will move to an intermediate position, in which the stem 31 is lifted for a shorter period of time. In other words, for the Diesel engine to operate normally, a balance will occur in which the shaft 12 is rotating at the identical speed as the lead motor 24.

An increase in load causes the Diesel engine to slow down and fall more or less behind the

lead motor 24. This, in turn, causes the cam 14 to slide along the drive shaft 12 so that a longer period of valve lift and fuel supply results, which acts to increase the speed of the Diesel engine until a new balance is obtained. A decrease in the load on the Diesel engine has an opposite effect.

The Diesel engine may be stopped by stopping the lead motor 24. The speed of the Diesel engine is determined by the speed of the lead motor 24. The difference of the momentary speed of the two units, Diesel engine and lead motor, governs the speed. The device acts as a differential governor, and as a fuel distributing device, during its operation. The lead edge 15a of the operator portion 15 of the cam 14 controls the valve 30 so that at correctly timed intervals in connection with the Diesel engine, the valve 30 is open to admit fuel oil under pressure into the cylinder or cylinders of the Diesel engine. The lead edge 15a marks the beginning of the valve lift, and this corresponds with the maximum compression in the cylinder and always corresponds with the same angular position of the drive shaft of the Diesel engine. The width of any particular section of the operator portion 15 controls the period of valve lift.

In Fig. 10 a modified form of the invention has been disclosed which distinguishes from the prior form in the fact that there is a separate starting motor. The lead motor 24' is not used for starting. Instead a starting motor 24x is provided which is connected with the drive shaft 12. This starting motor 24x may comprise a standard starting motor, or any other type of motor and arrangement by which the starting motor may be disconnected from the shaft 12 once the Diesel engine starts. In this form of the invention the lead motor 24' functions only to control the speed of the Diesel engine.

In other respects this form of the invention is similar to the previous form and like parts are indicated by like reference numerals. However, the starting operation is somewhat different. When starting, the lead motor 24' must also be operated simultaneously with the starting motor 24x so that the cam does not completely cut off the fuel supply. Another arrangement for starting would be to so design the fuel valves that they are set to supply fuel at idling speed when the cam is in its cutting off position.

In Fig. 11 still another modified form of the invention has been disclosed in which the device is used merely as a fuel oil distributing device. In this form of the invention the fuel oil inlet valve 55 cam 14 is manually controlled. One way to accomplish this is illustrated. It comprises a peripheral groove 40 formed on the cam 14 and engaged by a fork 42 on a follower 43 mounted on a rotatively supported screw 44. The arrangement is such that the screw 44 may be manually turned for shifting the cam 14 on the drive shaft 12. A separate starter motor 24x is provided for starting the Diesel engine.

In other respects this form of the invention is similar to the previous forms and like parts are indicated by like reference numerals.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I

claim as new and desire to secure by United States Letters Patent is:

1. In a device of the class described, a drive shaft, a screw coaxially mounted on said drive shaft, an internally threaded wheel threadedly mounted on said screw, a thrust bearing rotatively supporting said wheel, drive means driving said wheel, and catch elements on said screw on opposite sides of said wheel and cooperative with complementary catch elements on the sides of said wheel, whereby if said drive shaft rotates at a greater speed than said wheel said screw will move in one direction until certain of said catch elements engage and then said shaft will drive said drive means and if said drive shaft rotates at a slower speed than said wheel said screw will move in the other direction until the other of said catch elements engage and then said drive means will drive said shaft.

2. In a device of the class described, a drive shaft, a screw coaxially mounted on said drive shaft, an internally threaded wheel threadedly mounted on said screw, a thrust bearing rotatively supporting said wheel, drive means driving said wheel, and catch elements on said screw on opposite sides of said wheel and cooperative with complementary catch elements on the sides of said wheel, whereby if said drive shaft rotates at a greater speed than said wheel said screw will move in one direction until certain of said

5 catch elements engage and then said shaft will drive said drive means and if said drive shaft rotates at a slower speed than said wheel said screw will move in the other direction until the other of said catch elements engage and then said drive means will drive said shaft, said catch elements comprising projections on the sides of said wheel and on the ends of said screw.

3. In a device of the class described, a drive shaft, a screw coaxially mounted on said drive shaft, an internally threaded wheel threadedly mounted on said screw, a thrust bearing rotatively supporting said wheel, drive means driving said wheel, and catch elements on said screw on 10 opposite sides of said wheel and cooperative with complementary catch elements on the sides of said wheel, whereby if said drive shaft rotates at a greater speed than said wheel said screw will move in one direction until certain of said catch elements engage and then said shaft will drive said drive means and if said drive shaft rotates at a slower speed than said wheel said screw will move in the other direction until the other of 15 said catch elements engage and then said drive means will drive said shaft, said screw having enlarged end portions, and said catch elements comprising projections on the sides of said wheel and on said enlarged end portions.

PETER DAS.
